BEARING BOLSTER FOR SPINDLES

Filed Aug. 11, 1928

UNITED STATES PATENT OFFICE

ERVIN BOWKER, OF FALL RIVER, MASSACHUSETTS

BEARING BOLSTER FOR SPINDLES

Application filed August 11, 1928. Serial No. 298,909.

This invention relates to spinning spindles and is more particularly concerned with providing a simple, economical and reliable means for renovating a worn out bearing 5 bolster for such a spindle.

As is well known the usual iron bolster is loosely supported inside the fixed base and is provided with a projecting key near its upper end to engage a longitudinal groove 10 in a fixed hollow casing or base, which contains it. In practice these keys wear out quite rapidly and, furthermore, the interior bearing surface at the upper end of the bolster which supports the spindle blade laterally becomes enlarged by wear, so that for 15 both reasons the bolster becomes inefficient and is no longer suitable for use. The replacement of the external keys on the bolster is not only expensive but it results in a 20 large loss through breakage of the bolsters in attempting to repair them.

The present invention deals with this problem by providing an easily replaceable key 25 for locking the bolster against rotation in its containing base and also for compensating for the wear of the annular bearing surface inside the upper end of the bolster.

Generally speaking, this improvement comprises an endwise removable sleeve or 30 collar provided with an integral key so that when slipped over the upper reduced end of the bolster it serves as an interlocking means for keying or locking the bolster against rotation in the hollow base, and also serves to 35 provide a close fitting lateral or radial bearing at the upper end of the bolster for properly supporting the spindle blade at this point, instead of the bearing that has become unduly enlarged through wear in service. 40 This and other features of the invention will be particularly described in the following specification and will be defined in the claims annexed.

In the accompanying drawing I have illustrated a cheap and convenient form of replaceable collar or sleeve embodying the principles of this invention, in which

Fig. 1 is a side elevation on a somewhat enlarged scale showing the bolster equipped 50 with the key and bearing collar with the

containing fixed base indicated in dotted lines.

Fig. 2 is a vertical section through the base and bolster on the sectional plane 2-2 of Fig. 3. 55

Fig. 3 is a transverse section on the plane 3-3 of Fig. 1.

Fig. 4 is a perspective view showing the detail of the removable collar or sleeve.

The bolster-containing base or casing 1 is 60 of usual and well known construction, being provided with a vertical groove 1^a extending down from the top for a distance to receive the usual locking key projecting laterally from the upper end of the bolster. 65

The bolster 2 is of usual construction, except that its upper end is reduced for a distance of half an inch, more or less, according to convenience, leaving an annular shoulder at 2^a. 70

The replaceable key is shown in Fig. 4 and is preferably made of thin sheet stock, such as brass or other suitable material, which readily admits of being drawn by 75 drawing and forming dies into appropriate shape to serve its purpose. This collar is in the form of a hollow cylindrical shell 3,

whose upper end is turned inward and downward to form an interior skirt 3^a of smaller diameter which forms a lateral bearing surface of proper diameter to engage and laterally support the corresponding portion of the spindle blade 5. The outer member of this collar along one side is struck outwardly to form a laterally projecting rib or 80 key 3^b, while approximately opposite the rib 3^b a longitudinal portion of the metal is struck inwardly to form a concavo-convex 85 interior key 3^c, which is designed to fit into one of the usual vertical oil grooves 2^b formed on the exterior of the upper portion 90 of the bolster.

It will be seen that the interior key 3^c, when the collar is slipped over the upper reduced end of the bolster, will slide into the oil groove of the bolster, thus interlocking the collar with the bolster against relative rotation, while the external key telescopes into the key-way or internal groove 100 at the upper end of the base or casing, as

shown at 1^a to interlock the collar against rotation relative to the fixed casing or base. I have, therefore, a collar that can be readily slipped on and off the upper end of the bolster, which is formed with integral keys, external and internal, for engaging respectively the containing base member 1 and the loosely mounted bolster 2, so that rotation is prevented.

10 Furthermore, by forming the collar or sleeve with an interior skirt 3^a of the proper diameter to form a proper bearing support for this portion of the spindle blade, I compensate for the enlargement of this bearing by wear, since these collars are readily slipped on and off and are very inexpensive, as they can be formed very cheaply by suitable dies so that by their renewal from time to time, as the key and lateral confining bearing tend to become inefficient, the bolster is easily renovated in a form fully equal to a new bolster.

15 A further advantage of this construction is that existing bolsters may be easily fitted with these renovating collars merely by turning down the outside of the upper end portion of the bolster for a short distance to permit the locking and bearing collar to be slipped over the end of the bolster into operative position, as shown in Fig. 2. The life 20 of a bolster provided with this construction is indefinitely prolonged and the renovation of the bolster to make it thoroughly efficient is so easily and cheaply effected, that the spindles may be maintained at their highest efficiency instead of being kept in use for reasons of economy long after wear has rendered them relatively inefficient.

25 What I claim is:

30 1. In a spinning spindle the combination with a hollow base, a tubular blade-containing bearing bolster adapted to be loosely supported in said base, an endwise detachable slip collar adapted to slip over the upper 35 end of the bolster and having interlocking engagement exteriorly and interiorly with the base and with the bolster respectively to prevent rotation of the bolster.

40 2. A bearing bolster for a spindle adapted 45 to be mounted loosely in a containing base, embracing in its construction a tubular blade-containing bearing member whose upper end is of reduced external diameter, a slip collar formed to slip over the reduced upper end 50 portion of said bolster to permit easy removal and replacement, said collar being provided with an exteriorly projecting key for engagement with a bolster-containing base member and being also provided at another point in 55 its circumference with an internal projecting key adapted to form a tongue and groove sliding engagement with the exterior of said bolster, thereby preventing the rotation of 60 the bolster in said base.

65 3. A bearing bolster adapted to be loosely

70 supported in a hollow spindle base, embracing in its construction a tubular blade-containing bearing sleeve, and rotation preventing means comprising an endwise removable tubular member having a portion at one side struck up to form a longitudinal projecting rib having slidable engagement with a groove on the interior of the base and having on its other side an indented portion adapted to slidably engage a groove on the exterior 75 of the bolster to prevent rotation of the bolster in the base, while allowing the bolster the desired freedom of movement.

80 4. A bolster renewing member, embracing in its construction a tubular collar having exterior and interior ribs for interlocking engagement with a spindle base and the bearing bolster respectively, and having an interior annular bearing surface in its upper portion arranged to overhang the upper end of the 85 tubular bolster to afford a bearing of proper diameter for the spindle blade.

90 5. A bolster renewing device, embracing a tubular sheet metal collar, comprising exterior and interior annular members, the latter being shorter than the former and affording a blade-engaging upward extension of the bolster, while the former is provided with means for interlocking the bolster with the usual bolster-containing spindle base to prevent rotation of the bolster.

95 6. A detachable slip collar for a spindle bearing bolster, embracing a sheet metal shell of tubular form whose upper end portion extends inwardly and downwardly to form an interior annular lateral bearing member for a spindle blade, the outer member or shell being extended down below said bearing member to form detachable telescopic engagement with the upper end of the bolster and having rotation-preventing engagement with the bolster.

100 In witness whereof, I have subscribed the above specification.
